UNITED STATES PATENT OFFICE.

ADJUTOR LOUIS PHILIPPE TALBOT, OF MONTREAL, QUEBEC, CANADA.

PROPELLING MEANS FOR BOATS.

1,289,038.

Specification of Letters Patent. Patented Dec. 24, 1918.

Application filed July 28, 1917, Serial No. 183,304. Renewed November 11, 1918. Serial No. 262,094.

To all whom it may concern:

Be it known that I, ADJUTOR LOUIS PHILIPPE TALBOT, residing at 668 Fullum street, in the city of Montreal, in the Province of Quebec, in the Dominion of Canada, have invented certain new and useful Improvements in Propelling Means for Boats; and I do hereby declare that the following is a full, clear, and exact description 10 of the same.

The invention relates to propelling means for boats, and has for its object the devising of specially constructed oars or propelling means whereby the operator will face the 15 bow of the boat.

The invention will be better described with the aid of the accompanying drawings, in which Figure 1 is a side elevation of a 20 rowboat provided with the improved propelling means.

Fig. 2 is a cross section on line A—A of Fig. 1, the oars having been removed.

Fig. 3 is an enlarged side elevation of the 25 oar supports.

Fig. 4 is a front elevation of one paddle or oar.

Like numerals of reference indicate corresponding parts in each figure.

In the drawings:

30 1 is a boat, and 2 are brackets preferably secured to the outer sides of the boat, as illustrated in the drawings. The said brackets 2 are provided with upwardly projecting flanges 3 and 4 supporting the rollers 35 5 and 6 which are arranged one above the other and grooved in order to form a channel 7 therebetween, in which is inserted the rod 8.

The rod 8 is preferably curved at 9 and 40 bent so as to form a loop 10 to receive the paddle 11, and 12 is a handle provided at the outer end of said rod 8. The paddle 11 will be firmly held in the loop 10 by means of the wedge 13 inserted between said loop 45 and the end projecting therein. Said paddle is here shown as being secured at right angles relative to the rod 8, but it may be secured at any other suitable angle, that proves more convenient.

50 This attachment is preferably provided in pairs on the boat, and two or three pairs

or only one pair may be easily adapted to a boat.

One important feature of the invention lies in the fact that it is not necessary to be 55 an expert oarsman to propel a boat, and the paddles, being close to the sides of the boat, may prevent the boat from upsetting in rough weather.

Without departing from the spirit of the 60 invention, one roller only could be used in place of two, or both rollers could be eliminated as long as the surfaces between which the rod 8 will slide are smooth. These 65 rollers will undoubtedly make the operation easier by eliminating friction, but the device would operate with as much efficiency without any rollers.

What I claim as my invention is:—

1. A means for propelling boats, comprising a bracket suitably secured to said boat and adapted to receive a rod suitably mounted within said bracket and projecting therethrough, the outer end of said rod being curved in order to prevent the same 75 from being pulled out from said bracket; a paddle secured at a right angle in relation to said rod and rigidly secured thereto; and a handle at the end of said rod, substantially as described. 80

2. A means for propelling boats, comprising a bracket suitably secured to said boat and adapted to receive a rod suitably mounted within said bracket and projecting therethrough, its outer end being curved, the 85 said rod being bent at its other end so as to form a loop and a handle; and a paddle rigidly secured within said loop, substantially as described.

3. A means for propelling boats, comprising a bracket secured to said boat, provided with two upwardly projecting lugs; rollers mounted between said lugs, one above the other; a rod slidably mounted within said rollers, bent at one end, the other end of said rod being bent so as to form a loop and a handle; and a paddle rigidly secured within 90 said loop, substantially as described. 95

Signed at Montreal, Canada, this 23rd day of April, 1917.

ADJUTOR LOUIS PHILIPPE TALBOT.
